FIG.1.

FIG.2.

Inventor
Maurice K. Kaplan
By Chilton, Wiles, Davies, Hirsch & Dawson
Attorneys.

UNITED STATES PATENT OFFICE

125,570

DESIGN FOR A COMBINED ADJUSTABLE LAMP AND SUPPORT THEREFOR

Maurice K. Kaplan, Chicago, Ill., assignor to Nellie
J. Kaplan Company, Inc., a corporation of Illinois

Application April 1, 1940, Serial No. 91,406

Term of patent 3½ years

To all whom it may concern:

Be it known that I, Maurice K. Kaplan, a citizen of the United States, residing at Chicago, in the county of Cook and State of Illinois, have invented a new, original, and ornamental Design for a Combined Adjustable Lamp and Support Therefor, of which the following is a specification, reference being had to the accompanying drawing, forming a part thereof, in which:

Figure 1 is a front elevational view of a combined adjustable lamp and support therefor, showing my new design; and Figure 2 is a side elevational view thereof.

I claim:

The ornamental design for a combined adjustable lamp and support therefor, as shown.

MAURICE K. KAPLAN.
